UNITED STATES PATENT OFFICE

ADOLPH BREUSCH, OF NEW YORK, N. Y.

FLASH LIGHT AND MEDICAL HEATER

Application filed February 19, 1932. Serial No. 593,943.

This invention relates to new and useful improvements in a flashlight and medical heater.

The invention has for an object the construction of an article as above mentioned which is characterized by a body element open at the front and sides, and baffles hingedly connected on the rear side of the body element so as to extend across the open sides and be capable of deflecting the heat rays towards the front.

Furthermore, it is another object of this invention to arrange an arc mechanism to the front of the rear side of the body element so that when desired it may be conveniently used in conjunction with the device.

Furthermore, it is proposed to arrange a heating winding to the front of the rear side of the body element for the production of heat to be directed forwards.

This invention also proposes the provision of means for normally latching the baffles against hinging and releasable upon engaging the carbon elements of the electric arc together.

A still further object of this invention is the construction of a device of the class described which is of simple, durable construction, dependable in use and efficient in operation, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a device constructed according to this invention.

Fig. 2 is a side elevational view of Fig. 1.

Fig. 3 is a rear elevational view of Fig. 1.

Fig. 4 is a plan view of the device.

Fig. 5 is a fragmentary enlarged sectional view taken on the line 5—5 of Fig. 1.

Fig. 6 is a fragmentary enlarged sectional view taken on the line 6—6 of Fig. 1.

Fig. 7 is a horizontal sectional view taken on the line 7—7 of Fig. 6.

Fig. 8 is a schematic wiring diagram of the device.

The body element of the flashlight and medical heater is composed of a sheet bent so as to have a vertical rear side 10 and top and bottom horizontal portions 11. Thus the body element is open at the sides and at the front. Baffles 12 are hinged upon the sides of the rear portion 10 of the body element. These baffles are adapted to be moved to positions so as to close the open sides of the body or to any angular position so as to deflect heat from a heating element as herein-after more fully explained. Bolts 13 extend through the top and bottom portions 11 and through bosses 14 upon the baffle elements 12 to accomplish the hinged connection. Top and bottom flanges 15 extend from the top and bottom edges of the baffles 12 inwards so as to shield to a certain extent the passage of heat down and up when the baffles are in the open position and thus cause the heat to travel outwards.

An insulation slab 16 is mounted slightly spaced and to the front of the rear portion 10 of the body. The mounting is accomplished by screws 17 and bushing elements 18 interposed between the insulation slab and the rear portion 10. A heating winding 19 is supported upon a plurality of insulation members 20 mounted upon the front of the slab 16. The members 20 are so arranged that the heating winding 19 is of a great length compared with the area of the slab 16. Electric arc elements 21 and 22 are also supported upon the insulation slab 16. These electric arc elements are shunted across an electric circuit 23 which is connected in series with the winding 19. This is very clearly shown in Fig. 8.

The elements 21 and 22 preferably should be carbon as is used in arc lamps. The carbon element 21 is fixedly mounted by a set screw 24 in a block 25 secured upon the front of the slab 16. The carbon 22 is held in place upon a block 26 by reason of a set screw 27. The block 26 is pivotally supported upon the insulation slab 16. This pivotal support-

ing is accomplished by a pair of support elements 28 mounted on the slab 16 and engaging slightly into the sides of the member 26. A handle 29 is fixed upon a stem 30 attached upon the rear of the block 26. This handle allows pivoting of the carbon element 22. A stop screw 31 is threadedly engaged in a backing casing 32 secured upon the rear of the body portion 10. Resilient means in the form of a spring 33 act between a stem 30 and the casing element 32 so as to limit separation of the carbon elements 21 and 22 to a predetermined distance. The knob 29 extends through an opening 34 in the casing 32 so as to allow movement to cause the carbon elements 21 and 22 to be engaged with each other.

The front of the bottom element 11 of the body of the device is turned upwards as indicated by reference numeral 35 so that the ends thereof serve to form stops to limit the possible closing of the baffles 12 to positions so as to close the sides of the body element but allow the front to remain open. The body element is shown supported upon a stand 36 having a flat base 37 adapted to rest upon some flat surface. An electric cord 38 is shown engaging through a bushing 39 upon the casing element 32 and thereafter to conclude the circuit illustrated in Fig. 8. A plug 40 is electrically engaged upon the free end of the cord 38 so that it may be engaged into a live socket.

A means is also provided for holding the baffles 12 in various fixed pivoted positions. This means is so arranged as to release the baffles to allow changing their positions when the carbon elements 21 and 22 are in contact with each other. It should be recognized that when the carbon elements are in contact the arc is extinguished and will not blind or cause discomfort to a person attempting to adjust the baffles 12 so as to properly thrust the heat to the front. More particularly, each of the support elements 28 have forked outer ends straddling the edges of an opening 41 formed in the insulation slab 16 and through which the block 26 engages. These forked ends serve to slidably hold the members 28. Pins 42 engage through the ends of the support members 28 and through vertical elongated slots 43 in the slab 16 so as to limit motion of the elements 28 to the slightly vertical. Arms 44 project from the rear sides of the elements 28 and extend down and connect with a flat spring 45 secured at one end 46 to the front of the body portion 10. The spring element 45 has arms 47 terminating in upturned ends 48 adapted to engage through openings 49 in the flanges 15 of the baffles. These openings are arranged concentric with the hinged points of the baffles as clearly shown in Fig. 7.

The operation of the device consists in causing an electric current to heat up the

winding 19 and adjusting the baffles 12 so as to properly direct the heat to the front. The arc may be caused to operate by manually moving the handle 29 downwards against the action of the spring 33 until the carbon elements 21 and 22 engage. Then releasing the handle 29, the carbon elements will operate to a distance as controlled by the screw 31. This screw may be adjusted to vary the size of the arc. As the elements 21 and 22 separate they will draw the arc flame. If the arc is operating and it is desired to change the positions of the baffles 15, the handle 29 may be moved so that the carbon elements 21 and 22 engage each other thus extinguishing the arc flame. Upon front downward movement of the handle 29 the pivoted supports 28 will move downwards under the resilient action of the flat spring 45. This downward motion will cause the ends 48 to disengage from the openings 49 and allow changing of the position of the baffles 12. When the handle 29 is released the ends 48 will again engage the apertures 49 and hold the baffles in the new pivoted positions.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim is new and desire to secure by United States Letters Patent is:—

1. A flashlight and medical heater, comprising a body element open at the front and sides, baffles hinged upon the sides of the rear of the body element so as to be capable of closing the sides of the body, a heating winding supported to the front of the rear of the body, electric arc elements supported to the front of the rear of the body, a circuit including said winding in series and the arc elements shunted therein, means for holding said baffles in various pivoted positions, and said electric arc comprising a stationary carbon element, a pivoted carbon element, a handle connected with said pivoted carbon element and extending from the rear of the body element, a stop limiting separation of the carbon elements, and resilient means urging the movable carbon element into the separated position.

2. A flashlight and medical heater, comprising a body element open at the front and sides, baffles hinged upon the sides of the rear of the body element so as to be capable of closing the sides of the body, a heating winding supported to the front of the rear of the body, electric arc elements supported to the front of the rear of the body, a circuit including said winding in series and the arc elements shunted therein, means for

- holding said baffles in various pivoted positions, and said electric arc comprising a stationary carbon element, a pivoted carbon element, a handle connected with said pivoted carbon element and extending from the rear of the body element, a stop limiting separation of the carbon elements, and resilient means urging the movable carbon element into the separated position, said body element being formed from sheet material bent so as to have a vertical rear connected with horizontal top and bottom portions, and the bottom portion having an upturned front edge to limit the closing position of the baffles. 5
3. A flashlight and medical heater, comprising a body element open at the front and sides, baffles hinged upon the sides of the rear of the body element so as to be capable of closing the sides of the body, a heating winding supported to the front of the rear of the body, electric arc elements supported to the front of the rear of the body, a circuit including said winding in series and the arc elements shunted therein, means for holding said baffles in various pivoted positions, and said electric arc comprising a stationary carbon element, a pivoted carbon element, a handle connected with said pivoted carbon element and extending from the rear of the body element, a stop limiting separation of the carbon elements, and resilient means urging the movable carbon element into the separated position, a slab being supported to the front of the rear of said body element and said heating winding being mounted upon said slab. 20
4. A flashlight and medical heater, comprising a body element open at the front and sides, baffles hinged upon the sides of the rear of the body element so as to be capable of closing the sides of the body, a heating winding supported to the front of the rear of the body, electric arc elements supported to the front of the rear of the body, a circuit including said winding in series and the arc elements shunted therein, means for holding the said baffles in various pivoted positions, and said electric arc comprising a stationary carbon element, a pivoted carbon element, a handle connected with said pivoted carbon element and extending from the rear of the body element, a stop limiting separation of the carbon elements, and resilient means urging the movable carbon element into the separated position, the carbons of said electric arc being detachably supported in place. 25
5. A flashlight and medical heater, comprising a body element open at the front and sides, baffles hinged upon the sides of the rear of the body element so as to be capable of closing the sides of the body, a heating winding supported to the front of the rear of the body, electric arc elements supported to the front of the rear of the body, a circuit including said winding in series and the arc elements shunted therein, means for holding said baffles in various pivoted positions, and said electric arc comprising a stationary carbon element, a pivoted carbon element, a handle connected with said pivoted carbon element and extending from the rear of the body element, a stop limiting separation of the carbon elements, and resilient means urging the movable carbon element into the separated position, said baffles being formed with top and bottom flanges extending inwards so as to prevent heat motion upwards and downwards. 30
- In testimony whereof I have affixed my signature.
- ADOLPH BREUSCH. 130
